CASING FOR AN ELECTRIC HAIRSETTER

William J. Cook, Trumbull, Conn., assignor to
General Electric Company

Filed Mar. 24, 1972, Ser. No. 237,998

Term of patent 14 years

Int. Cl. D28—03

U.S. Cl. D86—10 E

FIG. 1.

FIG. 2.

FIG. 3.

FIG. 4.

FIG. 5.

FIG. 6.

FIG. 7.

FIG. 1 is a perspective view of a casing for an electric hairsetter embodying my new design;

FIG. 2 is a front elevational view thereof;

FIG. 3 is a top plan view thereof;

FIG. 4 is a right side elevational view thereof;

FIG. 5 is a bottom plan view thereof;

FIG. 6 is a rear elevational view thereof; and

FIG. 7 is a left side elevational view thereof.

I claim:

The ornamental design for a casing for an electric hair-setter, substantially as shown.
